(57) **CLAIM**

The ornamental design for a food waste disposer trim shell, as shown and described.

DESCRIPTION

FIG. 1 is a perspective view of the food waste disposer trim shell.

FIG. 2 is a front view.

FIG. 3 is a rear view.

FIG. 4 a side view.

FIG. 5 is a side view showing the side opposite that shown in FIG. 4.

FIG. 6 is a top view; and,

FIG. 7 is a bottom view.

The broken line showing of environment in the drawings is included for the purpose of illustrating only and forms no part of the claimed design.
